DISK TRIMMER

Frans O. Albertson, Sioux City, Iowa, assignor to
 Albertson & Company, Inc., Sioux City, Iowa,
 a corporation of Iowa

Application February 7, 1938, Serial No. 189,087

2 Claims. (Cl. 164—63)

The present invention relates to disk trimmers, and is particularly concerned with devices for trimming off the edges of the abrasive disks of the type which are used on electric sanding machines.

Such abrasive disks are usually subjected to the most wear at that area of the disk which is adjacent the outer edge of the face, and it is that portion of the disk which becomes filled with dirt and other foreign material, such as paint, during the abrading operation. Consequently, the abrasive disks may be used over and over again by applying them to a smaller supporting pad, after trimming off the worn edge.

One of the objects of the invention is the provision of an improved tool by means of which the used portion of an abrasive disk may be cut off.

Another object of the invention is the provision of an improved cutting tool by means of which the parts of an abrasive disk may be trimmed off and the disk put in proper position for use on a smaller supporting pad.

Another object of the invention is the provision of an improved disk cutting tool of the class described which is simple, sturdy, economical, and adapted to the quick and clean cutting or trimming of abrasive disks with a minimum amount of effort, in order to utilize fully all of the area of the abrasive material.

Another object of the invention is the provision of an improved disk trimmer which is provided with force-multiplying means for increasing the pressure applied to the trimmer, whereby the disk may be trimmed more quickly and easily.

Another object of the invention is the provision of an improved trimmer which has provision for supporting disks not only of different sizes, but having different sizes of centrally located shaft holes.

Another object of the invention is the provision of an improved disk trimmer which may be adjusted to standard sizes of disks very quickly and to various other intermediate sizes, with a minimum number of manual operations.

Another object is the provision of an improved method of trimming abrasive disks.

Other objects and advantages will be apparent from the following description and the accompanying drawings, in which similar characters of reference indicate similar parts throughout the several views.

Referring to the four sheets of drawings accompanying this specification,

Fig. 1 is a top plan view of a disk cutter constructed according to the present invention;

Fig. 2 is a side elevational view of the disk cutter;

Fig. 3 is a full size vertical sectional view, taken through the mechanism of the cutter on the plane of the line 3—3 of Fig. 1, looking in the direction of the arrows;

Fig. 4 is a sectional view, taken on the plane of the line 4—4 of Fig. 3, looking in the direction of the arrows;

Fig. 5 is a vertical sectional view, taken on the plane of the line 5—5 of Fig. 2, looking in the direction of the arrows, showing the details of construction of the disk supporting trunnion;

Fig. 6 is a view similar to Fig. 5, with the parts of the latter mechanism in a different position;

Fig. 7 is a vertical sectional view, taken on the plane of the line 7—7 of Fig. 3, looking in the direction of the arrows;

Fig. 8 is a diagrammatic illustration of one form of disk for which the disk cutter is adapted;

Fig. 9 is a similar view of another form of disk;

Fig. 10 is a fragmentary plan view of a portion of an abrasive disk which has been subjected to the action of the trimmer, but from which the used portion has not yet been broken off.

The present invention is an improvement over my prior Patent No. 2,066,381, issued January 5, 1937.

Referring to Figs. 1—3, 20 indicates in its entirety my improved disk trimmer, which is shown in connection with an abrasive disk 21, and is carried by a support 22, such as a table or work bench. The trimmer 20 has its mechanism supported upon a cast metal body 23, which may be substantially rectangular in plan, as shown in Fig. 1, and substantially rectangular in elevation at each of the sides thereof, as shown in Figs. 2 and 7.

The supporting casting or body 23 has a pair of side walls 24, 25, which are provided with laterally extending attaching flanges 26, 27 having apertures 28 for receiving the wood screws 29, which secure the trimmer to the table or bench 30.

22. The body 23 also has a top wall 30, and referring to Fig. 2, a left end wall 31 and right end wall 32.

The left end wall (see Fig. 3) extends down to the point 33. The top wall is thickened from 33 to a vertically extending aperture 34 to provide material forming a bearing 35 for a cutter shaft 36. The body is reinforced adjacent the slot 34 by a depending rib 37. The slot or aperture 34 extends from the bottom to the top of 35.

the body and provides space for the location of the cutter 38, which is carried by the shaft 36.

The shaft 36 comprises an elongated cylindrical member of such size as to be rotatably mounted in the bearing bore 35. At its right end it is provided with a reduced squared portion 39 for receiving the cutter 38, which has a squared aperture 40 of the same size. At this end the shaft 36 also has a reduced cylindrical threaded portion 41 for receiving a nut 42, which clamps the cutter 38 in place.

Washers 43, 44 are preferably disposed on each side of the cutter to serve as thrust bearings and to space the cutter body slightly from the wall of the slot 34.

The cutter 38 comprises a hardened steel member of substantially circular form, which is provided on its periphery (Fig. 7) with a multiplicity of inwardly extending V-shaped slots 45. These slots may be spaced in a random manner to provide knife edge formations 46 of different length with respect to the direction of the periphery of the disk. The cutter (Fig. 3) is substantially flat and of uniform thickness over its central portion, extending to a radius outside of the washers 43, 44; that is, to the point 47; but from the point 47 to the edge of the cutter, the cutter is tapered as at 48 to a sharp knife edge 46.

The left end of the shaft 36 (Fig. 3) supports a spacing sleeve 49 and has a reduced threaded portion 50 for receiving the threaded nut 51 and the crank 52, which has a threaded bore 53. The nut 51 is, therefore, adapted to act as a lock washer for securing the crank 52 against the annular shoulder 54.

The crank 52 may consist of a metal bar which may be slightly offset, if desired, intermediate its length, and which is provided with the threaded bore 53 at one end and with a smaller threaded bore 55 adjacent the other end. The smaller threaded bore 55 receives the threaded end of a knob-supporting pin 56, the head 57 of the pin retaining the knob 58 on the crank arm 59. Thus the cutter 38 is mounted to rotate with the shaft 36, and the crank 52 is adapted to rotate the shaft and cutter for a purpose further to be described.

The rear wall 32 of the trimmer body 23 is provided with a centrally located horizontally extending bore 60 for receiving the cylindrical end 61 of a guide bar 62, the rest of the guide bar being non-circular or rectangular in cross-section, as shown in Fig. 5.

A set screw 63 threaded into a suitable threaded bore in the bottom of the wall 32 is adapted to secure the bar 62 to the wall at substantially right angles thereto. The guide bar 62 may be provided at its outer end with an additional supporting foot in the form of a screw bolt 64, which is threaded into a threaded bore 65 in the bottom of the guide bar at its extreme end, the screw bolt 64 having its head in engagement with a spacer sleeve 66. The length of the screw 64 is then such that it aids in supporting that end of the guide bar 62.

The guide bar 62 may be provided with one or more stop members in the form of screw bolts 67, 68, which are located at the proper position for the slider 69 for predetermined sizes of disks. For example, the stop 67 is at the proper position for a seven inch disk, while stop 68 is in the proper position for the slider for a five inch disk, and when the slider 69 is against the wall 32 it is in proper position for a three inch disk. The numbers 3, 5 and 7 thus appear on the top of the

guide bar 62 adjacent the stops. Naturally, the screw 68 must be removed before the slider can be moved over to the three inch position against the wall 32.

The slider may also be located at any intermediate position or any position beyond the stop 67 to the end of the bar for intermediate sizes of abrasive disks, or for larger disks.

The slider 69 supports a shaft or trunnion 70 extending upward at right angles to the bar 62. Slider 69 may consist of a block of metal, such as steel, which is provided with a rectangular aperture 71 adapted to slidably receive the rectangular or square bar 62. Thus the slider 69 is slidably mounted on the bar 62, but is prevented from rotating, and is held in upright position. The slider 69 may be secured in any predetermined position by means of a thumb screw 72 which is threaded into a threaded bore 73 in slider 69, and the end of which engages the bar 62.

At its upper side it is provided with a cylindrical bore 72 which is adapted to receive with a tight frictional fit the reduced cylindrical end 73 of the stub shaft 70. The stub shaft 70 is formed with a middle cylindrical portion 74 and an end cylindrical head 75 of larger size, thus providing the annular shoulder 76 for retaining a sleeve 77 on the shaft 70. The larger cylindrical portion 75 serves as a trunnion or support for rotatably supporting the abrasive disk 21, having a relatively small central aperture 78.

The present device is, however, adapted to be used for supporting other abrasive disks 79, having a larger centrally located aperture 80, as shown in Fig. 9. For this purpose the shaft 70 slidably supports the sleeve 77.

The sleeve 77 is a metal member formed with a cylindrical body 81 having a centrally located bore 82 for rotating and sliding movement on the shaft 70. The body 81 has a pair of transverse slots, the slot 83 being relatively shallow, while the slot 84 is at right angles thereto, and is a relatively deep slot.

A metal pin 85 projects laterally from each side of the shaft 70 and is fixedly secured by a frictional fit in an aperture in the shaft 70 in such position that it will register with either of the slots 83, 84. The body 81 of sleeve 77 has a reduced cylindrical portion 86 which is also adapted to serve as a trunnion for an abrasive disk 79 having an enlarged aperture 80 fitting about the cylindrical portion 86.

When the sleeve 77 is in the position of Fig. 3, the pin 85 is in the slot 84 and the proportions and location of pin and slot are such that the upper end 87 of sleeve 77 is approximately on the same plane as the upper edge or cutting edge of the cutter 38 (Fig. 3). Thus the end 87 of sleeve 77 serves as a support for determining the proper level of the abrasive disk.

When the sleeve 77 is lifted so that the pin 85 emerges from slot 84, the sleeve 77 may then be rotated until slot 83 registers with pin 85, and dropped in that position. The sleeve is then in the position of Fig. 6, and the cylindrical portion 86 of the sleeve serves as a trunnion for the disks (Fig. 9) having the larger holes 83, the disk being supported upon the annular shoulder 88.

The annular shoulder 88 is then on a level with the upper edge of the cutter 38.

The body 23 of the disk trimmer is provided with a pair of upwardly projecting bearing lugs 91, 92 (see Fig. 1), Fig. 2 of which are provided with registering apertures 93 for receiving a bearing pin 94, which may be riveted in place, or

which may have a tight frictional fit in the apertures 93.

The pivot pin 94 pivotally supports a force-multiplying pressure lever 95 which has its left end (Fig. 3) mounted on the pin 94. The lever 95 may comprise a cast metal member which is provided with a substantially rectangular slot 96 on its lower side, and with a handle 97 which is elongated and extends over both the abrasive disks 21.

The lever 95 is provided with a longitudinally extending bore 98, which is in alignment with another threaded bore 99 located at the opposite side of the slot 96. A screw bolt 100 has its head 101 countersunk in counterbore 102 and has its threaded end threaded into the vertical bore 99.

The screw bolt 100 rotatably supports a soft steel roller 103 which has an outer cylindrical surface 104 located to engage the top of an abrasive disk 21 when the disk is engaging the cutter 38. The slot 96 is of sufficient width to receive not only the roller 103, but a plurality of washers 105, and the washers 105 may be used to change the position of the roller 103 when the surface 25 of the roller 103 immediately above the cutter 38 has become worn. After long service a groove will eventually wear in the roller 103 above the cutter 38 and retard the cutting. Then one of the spacer washers 105 may be moved over to 30 the right of the cutter 38, by taking out the screw bolt 100 and replacing it, and then a new surface on the roller 103 will be in position above the cutter 38.

The lever 95 has an end surface 106 adapted 35 to serve as a stop, engaging the sleeve 48 or end of crank arm 59 when the lever 95 is pivoted from the full line position of Fig. 3 to the dotted line position of Fig. 3. In the dotted line position of Fig. 3 the stop surface 106 is supporting the lever 40 95, which moves far enough so that its weight is shifted from the right side of the pivot pin 94 to the left side thereof in Fig. 3. Thus the lever 95 is self-supporting in the dotted line position, which it assumes when the operator is placing 45 or removing the abrasive disk 21.

The operation of the present disk trimmer is as follows:

The sleeve 77 is adjusted to the position of Fig. 5 or Fig. 6, depending upon the size of hole in the 50 abrasive disk 21 or 79. Assuming that disk 21, with the smaller hole, is to be used, sleeve 77 is in the position of Fig. 3; and with the lever 95 in the dotted line position the disk 21 may be placed upon the trunnion 75. The slider 69 may 55 then be adjusted by loosening the thumb screw 89 and sliding the slider along the bar 62 until the position of the edge of the disk 21 with respect to the cutter is as desired; that is, the disk is moved until it is observed that the cutter will trim off the desired amount, which would be the 60 worn or filled portion of the abrasive disk.

The disk is applied to the trimmer with its abrasive side up, so that the cutter engages the smooth or paper side of the abrasive disk 21. 65 The roller 103 engages the abrasive side of the disk.

The operator then applies pressure to the roller 103, which in turn engages the abrasive disk and forces it against the cutter 38. This pressure is 70 applied by pushing down on the hand lever 95. A considerable amount of pressure may then be applied with a minimum amount of effort, due to the location of the cutter adjacent the point of pivot 94, and due to the length of the hand lever 95.

With the pressure thus applied, the operator rotates the crank 52 with his other hand by means of knob 58, thus also rotating the shaft 36 and the cutter 38. The cutter teeth or knives 46 bite into the fiber or base material of which the abrasive disk is constructed and serve to cause the abrasive disk to rotate on the trunnion 75 as the cutter rotates, the teeth in effect forming their own interlocking depressions in the bottom side of the abrasive disk.

Depending upon the thickness and toughness of the abrasive disk backing, the disk may be rotated once, twice, or more times, the knives 46 cutting in more deeply on each successive rotation, but it is generally only necessary to effect 10 one rotation of the abrasive disk 21, during which the knives will produce a plurality of spaced cuts in the lower side of the abrasive disk, as shown in Fig. 10. These spaced cuts practically go through the backing and abrasive facing of the 15 disk 21, but the trimmed edge may still be retained on the abrasive disk and may then be removed by a tearing operation along the dotted and punched line 107 (Fig. 10).

During the rotation of the abrasive disk the 20 roller 103 rotates but serves as a backing for pressing the abrasive disk against the cutter.

The disks may thus be trimmed neatly and cleanly with a minimum amount of effort and again used on a supporting pad of smaller size 25 so as to utilize all of the area of the abrasive disk down to the smallest size, which is approximately three inches.

My improved method of trimming abrasive 30 disks comprises pressing the rear side or backing 35 of an abrasive disk against a knife and cutting in said rear side of the abrasive disk a plurality of spaced indentations. This may be done by feeding the disk to the knife in a rotary direction, and thereafter the trimmed portion may be 40 broken or torn from the disk to effect a clean cut at the point of application of the knife.

The present disk trimmer is adapted to trim the abrasive disks, which have a particularly tough backing, with greater facility and greater ease than any of the devices of the prior art, including my own prior patented device mentioned above. It may be adjusted to any convenient size of abrasive disk and to one or more sizes of centrally located abrasive disk apertures. It is 45 adapted to be used for a longer period of time 50 without dulling the cutter, and greater pressure may be applied to the disk and cutter with less effort, so that the disks are trimmed much more quickly than by means of the prior art devices.

While I have illustrated a preferred embodiment of my invention, many modifications may be made without departing from the spirit of the invention, and I do not wish to be limited to the precise details of construction set forth, but desire to avail myself of all changes within the 55 scope of the appended claims.

Having thus described my invention, what I claim as new and desire to secure by Letters Patent of the United States, is:

1. In a trimmer for abrasive disks of the type having a centrally located aperture, the combination of a base adapted to be secured to a fixed support, said base having a transversely extending bearing and a drive shaft in said bearing, a crank carried by the outer end of said shaft, and a cutter wheel carried by the opposite end of said shaft and fixedly secured thereto, said cutter wheel having a sharp peripheral edge separated by a plurality of slots forming radially projecting knife-like teeth adapted to engage in the back 75

- of a disk to form indentations and drive the disk, and a support for the disk comprising a guide member carried by said base and projecting substantially parallel to said shaft, said guide member being provided with a slider, and said slider being adapted to be received in the aperture of said disk for rotatably supporting the disk, said base having a pressure lever pivotally mounted thereon above said shaft, said pressure lever overhanging said trunnion and being provided with a cylindrical pressure roller located above said cutter and rotatably mounted upon a shaft extending substantially parallel to the cutter shaft when the roller is engaging a disk whereby a disk may be located on said trunnion, with its abrasive side engaging said roller, and by rotating said crank and pressing downward on said lever said cutter will dig into the back side of the abrasive disk to form indentations and the teeth of said cutter will drive said disk, causing it to rotate about said trunnion, said roller forcing said disk against said cutter without bringing the cutter into engagement with the abrasive, whereby the indentations form a circular line about said disk, and the part of the disk outside of that line may be broken off by the hand, the length of said lever being such that sufficient force may be applied to the rear side of an abrasive disk with the cutter, without forcing the cutter through the abrasive and into engagement with the roller.
2. In a trimmer for abrasive disks of the type having a centrally located aperture, the combination of a base adapted to be secured to a fixed support, said base having a transversely extending bearing and a drive shaft in said bearing, a crank carried by the outer end of said shaft, and a cutter wheel carried by the opposite end of

said shaft and fixedly secured thereto, said cutter wheel having a sharp peripheral edge separated by a plurality of slots forming radially projecting knife-like teeth adapted to engage in the back of a disk to form indentations and drive the disk, and a support for the disk comprising a guide member carried by said base and projecting substantially parallel to said shaft, said guide member being provided with a slider, and said slider being adapted to be received in the aperture of said disk for rotatably supporting the disk, said base having a pressure lever pivotally mounted thereon above said shaft, said pressure lever overhanging said trunnion and being provided with a cylindrical pressure roller located above said cutter and rotatably mounted upon a shaft extending substantially parallel to the cutter shaft when the roller is engaging a disk whereby a disk may be located on said trunnion, with its abrasive side engaging said roller, and by rotating said crank and pressing downward on said lever said cutter will dig into the back side of the abrasive disk to form indentations and the teeth of said cutter will drive said disk, causing it to rotate about said trunnion, said roller forcing said disk against said cutter without bringing the cutter into engagement with the abrasive, whereby the indentations form a circular line about said disk, and the part of the disk outside of that line may be broken off by the hand, said roller shaft being provided with a plurality of spacers mounted thereon, whereby the position of the roller may be shifted to bring new bearing surfaces of the roller into alignment with said cutter.

FRANS O. ALBERTSON.
